& Richstein, ATTORNEYS.

UNITED STATES PATENT OFFICE

PHILIP S. CASE, OF NIAGARA FALLS, NEW YORK, ASSIGNOR TO ELECTRO METALLURGICAL COMPANY, A CORPORATION OF WEST VIRGINIA

SPRAY GUN

Application filed June 4, 1929. Serial No. 368,298.

My invention relates to spray guns for producing a low velocity spray of comminuted solids combined with liquid and gas so as to form moistened coatings of the solid material.

One of the purposes of my invention is to provide devices which will produce coatings of powdered solids on fragile objects, which objects are injured by high velocity sprays.

Another purpose of my invention is to provide devices which are capable of producing a composite spray consisting in part of moistened solids and gas of high moisture content and in part of moistened solids of low moisture content.

Another purpose of my invention is to provide a device of few parts and of simple construction which may be incorporated in a small sized nozzle in which the constituents of the spray may be easily regulated and disassemblage of the device for the purpose of cleaning, may be quickly and easily effected.

In the drawings constituting a part hereof, Fig. 1 is a view in elevation and partially

25 in cross section of a spray gun,

Fig. 2 is an elevational view of a nozzle,

20 Fig. 3 is an elevational view of a modified form of nozzle,

Fig. 4 is a cross sectional view of the head of 25 the gun taken along the line IV—IV of Fig. 1, and

Fig. 5 is a cross sectional view of a portion of the head of the gun taken along the line V—V of Fig. 4.

30 The spray gun is capable of being used with gases, liquids and solids of various kinds and densities but will be described in connection with its use for coating sand molds with coatings of metal powders and a binder of sugar solution in which air is used to produce the suspensions of solids and liquid.

35 The spray gun has a handle portion which may comprise a pipe 1 for conducting mixtures of solids and air, a pipe 2 for conducting liquid and a pipe 3 for conducting air. The pipes are held together by a clamp 4 near one end of the pipes and by screwing the other ends into a threaded head 5 which is provided with bores 6, 7 and 8 corresponding to the 40 passages in the pipes 1, 2 and 3 respectively.

Valves 10 and 11 are mounted on the outer ends of pipes 2 and 3 for regulating the supply of liquid and air. The bore 6 and its corresponding passage through the pipe 1 are provided with a wear-resisting lining to prevent the wearing away of the metal parts of the gun. The lining may consist of a gum rubber lining 12 which is secured in the pipe in any convenient manner and extends from the nipple 13 to the discharge terminus of the 55 passage 6 in the head 5. A suspension of comminuted solids in air is supplied to the gun through a pipe which is connected to the nipple 13, a source of liquid under pressure is connected to the gun through the union 14 60 and a supply of air under pressure is connected through the union 15 to the pipe 3.

65 The head 5 may be formed so as to project the spray at an angle to the axis of the handle. On the extremity of the head 5, 70 is a nipple 20 as shown in Figs. 2, 3 and 5 which forms the extremity of the bore 6. The nipple is detachably mounted on the head by providing a screw connection. A small groove 21, as shown in Figs. 2 and 3, preferably about $\frac{3}{2}$ of an inch across and about $\frac{1}{4}$ of an inch long is cut in the exterior surface of the nipple 20 parallel to the axis of the passage 6. The groove 21 provides a mixing chamber and a discharge port for the liquid binder and air mixture. The groove 21 is connected with forking grooves 22 and 23. The liquid binder is supplied to the groove 21 through the groove 22 and air is supplied through the groove 23. An exterior sleeve 24 which is given a snug sliding fit with the nipple 20 has a smoothly faced flange 25 which is mounted on a corresponding facing of the member 5 by means of a nut 26. It has been found that a short small groove 21 does not tend to become filled with an accumulation of hardened binder and that mixtures of solids and liquid do not tend to collect on the end of the nozzle and clog the small port.

90 Referring to Fig. 4, an annularly disposed groove 27 which extends only partly around the nipple is cut in the facing of the member 5 so as to form a connection between the terminus of the bore 7 and the groove 22; 100

and a similar connection groove 28 extends between the terminus of the bore 8 and the groove 23. The seating of the flange 25 on the facing of the head member 5 prevents leakage of air or liquid from the passages 27 and 28, and the sliding fit of the sleeve 24 on the nipple 22 prevents leakage of air and liquid from the grooves 22 and 23.

Efficient operation and control of the spray depends in large measure upon clean, free passages for air and liquid binder. Efficiency and constant operation of the gun over long periods is facilitated by the arrangement of the small passages which are formed between the surfaces of stationary and demountable parts. Their arrangement provides means to open the small passages lengthwise and to expose to view the exact condition of the passages.

The nipple 20 is preferably provided with at least two mixing chambers and discharge ports 21 and with corresponding forking air and liquid grooves 22 and 23 so that each of the grooves 21 has a connection with the air supply and a connection with the liquid supply. Where two ports 21 are used, they are preferably positioned diametrically opposite each other but more than two or less than two discharge ports may be used and they may be located in the end of the nozzle in other positions than those shown in the drawing. Two ports 21 give good results and it has been found in practice that less frequent adjustment of the liquid and air is necessary and that the coating of irregular surfaces is more easily controlled with a small number than with a large number of ports 21.

Where the discharge of the mixture of liquid and air consists of a small number of grooves 21, as for example two grooves, the composite spray which is formed externally of the nozzle, consists of two portions of solids suspended in air which contain a relatively large amount of moisture. The remainder of the spray is drier. The relative amount of moisture in the two moisture-rich portions may also be varied by rotating the gun about the axis of the nozzle 20 so that the spray of heavy solids and air will descend more or less away from one jet of mixed liquid and gas and toward the other. In this way, the quality of the composite spray may be changed so that one portion of the spray will be largely solids and air and another portion will be largely liquid and air. The latter regulation is useful to produce various degrees of wetness in applying different parts of the coating.

In the normal operation of the gun, the spray of solids and air projected from the passage 6 is a low-density low-velocity mixture of large volume and the spray at the nozzle from the grooves 21 is a comparatively high-velocity low-density spray of small volume. Because of the tendency of the sprays

to expand and diffuse they combine within a short distance of the nozzle, the spray of higher velocity supplying energy to carry on the solid particles at a velocity commensurate with their nozzle velocity. The spray of liquid and air also produces a turbulence which helps to produce a moistening of all the solid particles.

Because of the high density of the solids and the low velocity of the spray of solids and air, the solids tend to segregate in the lowest parts of the passage 6. Therefore, the gun is usually operated so that the grooves 21 are in a vertical plane so that the lower of the two sprays will commingle directly with the most dense mixture of air and solids. When the position of the surface to be coated requires that the nozzle be turned through an angle, I provide a nozzle as shown in Fig. 3 with the forked grooves 22 and 23 curved around the nozzle so as to connect with grooves 21. Thus, the grooves are displaced through an arc required by the new position of the gun.

A regulated and constant supply of a low-density low-velocity mixture or cloud of finely divided metal particles and air may be produced by any convenient means and conducted through the passage 6. In operation the velocity of this mixture may conveniently be regulated so that the stream of solids will travel 8 or 10 inches from the nozzle before the general course of the stream is vertical. The supplies of air and liquid binder are next regulated by opening the valves 10 and 11 so that a spray of the desired liquid content and sufficient velocity is produced to moisten substantially all of the solids at a short distance from the nozzle, say 4 or 6 inches. To produce a spray having a small portion of drier solids and a portion of more moist solids than that contained as an average in the spray, the nozzle may be held close to the surface to be coated or the nozzle may be turned so that the grooves 21 are moved out of the vertical plane. In making a coating of powdered metal the gun is usually moved back and forth or given a rotary motion so that the coating of solids on all parts of the coated mold will have a uniform moisture content.

Although I have described certain specific embodiments of my invention I do not intend to limit my invention thereto. It is to be understood that modifications of the device described herein, may be made without departing from my invention. Therefore, I desire to be limited only by the prior art and by the invention as defined in the annexed claims.

I claim:

1. A spray gun comprising a head having a bore for conducting gas, a bore for conducting liquid and a bore for conducting a mixture of solids and gas, a terminal member on the head having a discharge orifice

- for the mixture of solids and gas, said member having a groove therein to conduct gas, a groove to conduct liquid and a communicating groove to mix gas and liquid, and means in said head to form connections between the grooves in said projecting member and the liquid and gas bores in the head.
2. A spray gun comprising a head having a bore for conducting gas, a bore for conducting liquid and a bore for conducting a mixture of solids and gas, a terminal member on the head having a discharge orifice for the mixture of solids and gas, said member having a groove therein to conduct gas, a groove to conduct liquid and a communicating groove to mix gas and liquid, and means in said head to form separate connections between the gas groove and bore and the liquid groove and bore respectively.
3. A spray gun comprising a head having a bore for conducting gas, a bore for conducting liquid and a bore for conducting a mixture of solids and gas, a projecting member on said head having a groove for mixing and discharging a mixture of liquid and gas, a faced portion on said head cutting across the gas bore and the liquid bore and having annularly disposed grooves for conducting gas and liquid respectively, said projecting member having grooves connecting the annularly disposed grooves with the discharging groove, a closely fitting sleeve on said projecting member forming passages with the grooves in the projecting member, a flanged member on said sleeve seated on the faced portion of said head so as to form passages with the grooves in the head, and means to engage the flange and secure the sleeve to the head.
4. A spray gun comprising a head, a tubular terminal member having an axially disposed bore for discharging a mixture of solids and gas, means on said tubular terminal member to mix liquid and gas, means to conduct liquid to said mixer and means to conduct gas to said mixer, said mixing means having a discharge port situated at the side of the axial terminus of the bore and directed parallel to the axis of said bore.
5. A spray gun comprising a head, a tubular terminal member having an axially disposed bore for discharging a mixture of solids and gas, means on said tubular terminal member to form mixers for liquid and gas, means to conduct liquid to said mixers, and means to conduct gas to said mixers, said mixers being disposed annularly around said axial bore and having discharge ports around the discharge end of the axial bore and directed parallel to the axis of said bore.
6. A spray gun comprising a head, a tubular terminal member having an axially disposed bore for discharging a mixture of solids and gas, means on said tubular member to form a plurality of mixers for liquid
- and gas, means to conduct liquid to said mixers, and means to conduct gas to said mixers, said mixers being spaced equally and annularly around the discharge end of said axial bore, each one of said mixers having a discharge port directed parallel to the axis of the bore.
7. A spray gun comprising a head, a tubular terminal member having an axially disposed bore for discharging a mixture of solids and gas, means on said tubular member to form a plurality of mixers for liquid and gas, means to conduct liquid to said mixers, and means to conduct gas to said mixers, said mixers being spaced equally, diametrically and annularly around the terminus of said axial bore, each one of said mixers having a discharge port directed parallel to the axis of said bore.
8. A spray gun comprising a handle, having a passage for conducting a mixture of solids and gas, a passage for liquid and a passage for gas, means on said handle to regulate the supply of liquid and gas, a head having bores coextensive with said passages, a faced portion on said head having a groove connected with the gas bore and a groove connected with the liquid bore, a demountable tubular terminal member having a forked groove in the exterior surface thereof with branches connected with the liquid and gas grooves of the head and one branch forming a mixing chamber for liquid and gas and a discharge port for said mixture, a fitted sleeve around said terminal member, a flange on said sleeve adapted to form a seal with the faced portion of said head, and means engaging said head and flange to secure the sleeve.

In testimony whereof, I affix my signature. *PHILIP S. CASE.*
